(57) **CLAIM**

We claim the ornamental design for an engagement shield
for a tourniquet cuff, as shown and described.

DESCRIPTION

FIG. 1 is a perspective view of the engagement shield for a
tourniquet cuff showing a left side, a top and a front.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a top plan view of the engagement shield of FIGS.
1-7 shown in relation to a first exemplary tourniquet cuff;
and,

FIG. 9 is a top plan view of the engagement shield of FIGS.
1-7 shown in relation to a second exemplary tourniquet cuff.
The broken line showings of tourniquet cuffs illustrate the
environment of the claimed design and form part no part
thereof.

1 Claim, 5 Drawing Sheets
